UNITED STATES PATENT OFFICE.

BEREL McCACKEN AND CELESTER PIOTT, OF MOUNT PLEASANT, PENNSYLVANIA,
ASSIGNORS TO BRYCE BROTHERS COMPANY, OF MOUNT PLEASANT, PENNSYLVANIA, A CORPORATION OF PENNSYLVANIA.

DESIGN FOR GLASS.

Application filed May 3, 1922. Serial No. 2,052. Term of patent 14 years.

To all whom it may concern:

Be it known that we, BEREL McCACKEN and CELESTER PIOTT, both citizens of the United States, residing at Mount Pleasant, in the county of Westmoreland and State of Pennsylvania, have invented a new, original, and ornamental Design for Glass, of which the following is a specification, reference being had to the accompanying drawing, forming part thereof, in which is shown

a piece of glass having a plurality of elliptically-shaped raised portions, giving a dappled effect.

We claim:

The ornamental design for glass as shown. In testimony whereof, we have hereunto set our hands.

BEREL McCACKEN.
CELESTER PIOTT.
